UNITED STATES PATENT OFFICE.

AUSTIN HOPKINSON, OF GUIDE BRIDGE, ENGLAND.

METHOD OF AND APPARATUS FOR DRIVING TUNNELS FOR MILITARY OR OTHER PURPOSES IN EARTH OR SOFT ROCK.

1,347,332.

Specification of Letters Patent. Patented July 20, 1920.

Application filed August 6, 1917. Serial No. 184,722.

To all whom it may concern:

Be it known that I, AUSTIN HOPKINSON, a subject of the King of Great Britain, residing in Guide Bridge, England, have invented a certain new and useful Improved Method of and Apparatus for Driving Tunnels for Military or other Purposes in Earth or Soft Rock, of which the following is a specification.

10 The invention relates to means for driving tunnels for military or other purposes in earth or soft rock.

In the system according to the invention, in the tunnel shaft, or outside the entrance 15 to the tunnel, if there is no shaft, are placed an electric motor or other suitable means for operating a belt conveyer which removes the debris and a belt reservoir for enabling the working length of the conveyer belt to be altered as required.

20 The motor is geared to the rollers driving the belt conveyer and the debris from the latter is discharged into a hopper and then into sand bags or other convenient receptacles.

25 When an advance corresponding to a predetermined and constant length has been made, the excavating machine is withdrawn on its slides through this distance and tubing comprising hinged members, which can be readily passed when folded together along the tunnel without interfering with the excavating and conveying machinery, is put into position; at the same time a section 30 of flooring is laid.

35 If a short section of conveyer cover has been previously placed in position immediately behind the excavating machine, this section is removed and a longer section inserted and the length of the conveyer belt adjusted accordingly by the belt reservoir; each short section of the conveyer cover corresponds to a section of the tubing and flooring, and the full length of each conveyer cover section is a multiple of this 40 standard section. When a full length section of the cover is placed in position an extra roller frame is also added.

45 The excavating machine comprises a frame fed forward on slides by the hands or feet of an operator, who is provided with a seat on the framework; a shaft is driven by suitable gearing through the medium of a universal joint from the conveyer and 50 rotates a telescopic sliding member. This

member is connected by a universal joint to a tube containing a spiral for conveying to the belt conveyer the debris removed from the working face of the tunnel by a helical cutter secured to the rotating shaft 60 of the spiral conveyer. The tube can be swiveled by the operator about both a horizontal and a vertical axis, within limits provided by a guide frame conforming on a smaller scale to the cross section which may 65 be of any form of the tunnel and secured to the sliding frame of the machine. The position and dimensions of the guide frame are such that the cutter can traverse every part of the working face of the tunnel. 70

Debris falling clear of the spiral conveyer is arranged to drop on an inclined apron from which it is easily raked up into the conveyer.

An important feature of the invention 75 consists in the arrangements by which, when the excavation has been advanced by the required length, sections of tubing, flooring and conveyer cover, previously prepared and of constant dimensions, can be placed 80 in position without the removal of any of the machinery.

As the operation can be effected noiselessly, it is especially suited to military purposes.

85 The accompanying drawings represent an example of an excavator and conveyer according to the invention. Figure 1 is a side elevation and Fig. 2 a plan showing more particularly the excavator and its attachments. Fig. 3 is a side elevation and Fig. 4 a plan of the driving gear of the conveyer. Fig. 5 shows a section of the tunnel; Figs. 6, 7 and 8 are, respectively, a side elevation, an end elevation and a plan of a 90 portion of the conveyer.

A tube 1 contains a worm conveyer 2 armed at the front end with a helical cutter 3. The tube 1 is carried by the frame 4 which slides on guides 5 carried by frames 100 5'. The frame 5' is carried on runners 6 so that it may easily be moved forward or backward. The rear end of the tube 1 is supported in trunnions 6' (Fig. 5) about which it can turn in a vertical plane; the 105 trunnion arms are connected to a vertical socket pin 7, pivoted in the frame 4, which allows the tube 1 to turn in a horizontal plane. The tube can consequently be moved in any required position by means of han- 110

dles 8 under the control of a driver on a seat 9. The movement of the tube is limited by a frame 10, which has internally but on a smaller scale the cross section of the tunnel to be driven. A dash pot, air cylinder or other suitable device (not shown) may be applied to steady the movement of the tube and prevent any appreciable vibration.

- 10 The worm conveyer and cutter are rotated by the telescopic shaft 11 which is provided at each end with universal couplings 12 and 13 and is driven through bevel wheels 14 and chain gear 15 from a roller 16 rotated by the belt 17 of the conveyer. The driver can feed or retract the cutter and worm conveyer by sliding the frame 4 on the guides 5 and can cause the rotating cutting tool to traverse the whole surface of 20 the end of the tunnel.

The excavated material passes along the worm conveyer 2 until it falls through a vent 18 upon the belt 17 by which it is conveyed to the entrance of the tunnel. The belt is guided by rollers 19.

25 The driving gear for the conveyer (Figs. 3 and 4) is usually placed outside the entrance to the tunnel, or, when the latter has attained a length greater than the length of 30 the conveyer, in an enlarged section of the tunnel. The motive power may be an electric motor 20 driving through suitable gearing rollers 21, 22, which are geared together by spur wheels 23, 24. The conveyer belt 17 is driven by the rollers 21, 22 and is guided by rollers 25 to a belt reservoir 26, which consists of a series of rollers 27 in a suspended frame 28. On lowering the frame an extra length of belt becomes available for 40 the conveyer in the tunnel.

The material excavated and conveyed along the belt is thrown off the latter into a hopper 29, which may be provided with a vent 30 for filling sandbags or other receptacles, and these or the material may be removed by an elevating conveyer out of the shaft. In the arrangement shown, the motor and other parts are carried on cross-girders 31 which are connected by sockets to 45 the driving-roller frame and to adjustable sockets 32 on the shaft lining. Water in the tunnel drains away by a pipe 33 and a pipe 34 is connected with a fan for ventilating the tunnel.

50 The conveyer, a portion of which is shown in Figs. 6, 7 and 8, consists of frames 35 carrying horizontal rollers 37 which hold up the loaded side, and rollers 36 which hold up the idle side of the belt 17.

60 The rollers 37 have spindles fitting into slots to allow them to be removed or placed in position without uncoupling the belt. The frames 35 are connected by covers 38, 39 which hold them in position and are attached to them by pins 40 fitting into socket-

ets on the frames. The short cover 38 is the same length as one section of the tunnel-lining. This cover can be replaced by others of twice and three times the length; the full length cover 39 is four times as long as 70 the cover 38.

When the excavator has cut a length equal to one section of tunnel-lining, the belt reservoir is lowered, and the conveyer cover nearest the excavator is replaced by one of 75 the next largest size, and so on, until a further roller-frame is required, after which the shortest cover is inserted and the process repeated, the excavator being pushed forward on its runners the required distance at 80 each stage.

The tunnel-lining (Fig. 5) consists of two, three, or more members, 41, hinged together. A loose member 42 may be inserted in a slotted hinge 43 and pressed into position and 85 held at the other end by a fixed flange 44 and a sliding flange 45. Each length of lining is formed so as to fit into the preceding length. A floor 46 is provided resting on the tunnel-lining and leaves a space 47 90 for the water to drain away, and for the ventilating air to be exhausted from the leading end of the tunnel. It will be seen that these sections of lining may be taken into the tunnel folded up and inserted in position as soon as sufficient length has been excavated.

Having thus described the nature of the said invention and the best means I know of carrying the same into practical effect, I 100 claim:

1. An excavator for tunneling, comprising, in combination, a cutter, means for operating the cutter in any plane, a shaft carrying the cutter, supports for the shaft, and 105 a guide frame in advance of said supports limiting the positions of the cutter and similar in outline to the cross-section of the tunnel to be driven.

2. An excavator for tunneling, comprising, in combination; a worm conveyer free to move in any plane, a helical cutter secured to 110 said worm conveyer, and a guide frame limiting the positions of the cutter and similar in outline to, but of smaller dimensions 115 than, the cross-section of the tunnel to be driven.

3. An excavator for tunneling, comprising, in combination, a cutter, a guide frame for limiting the range of movement of said 120 cutter, said guide frame being similar in outline to but of smaller dimensions than the cross-section of the tunnel, and said cutter being movable into any position within the limits prescribed by said frame, and means 125 for operating said cutter in any position including a telescopic shaft provided at each end with a universal coupling and connected to said cutter.

4. An excavator for tunneling, comprising 130

- in combination a cutter, means for operating the cutter in any plane, a guide frame limiting the motion of the cutter and conforming in outline to the cross section of the tunnel, 5 a belt conveyer, rollers driven by the belt conveyer and gearing operated by the rollers for imparting rotational movement to the said cutter.
5. An excavator for tunneling, comprising 10 in combination a cutter, a belt conveyer, rollers driven by the belt conveyer, gearing operated by the rollers for imparting rotary movement to the said cutter and a belt reservoir comprising a suspended frame and 15 rollers thereon.
6. An excavator for tunneling, comprising in combination a cutter, a telescopic shaft provided at each end with universal couplings, a worm conveyer driven by the said 20 telescopic shaft, a belt conveyer, rollers driven by the belt conveyer and gearing operated by the rollers for rotating the said telescopic shaft.
7. An excavator for tunneling, comprising 25 in combination a cutter, means for operating the cutter in any plane, a guide frame limiting the motion of the cutter and conforming in outline to the cross section of the tunnel, a belt conveyer, rollers over which said conveyer moves, and a telescopic shaft driven by said rollers and adapted to rotate said cutter.
8. An excavator for tunneling, comprising in combination a cutter movable into any 35 plane, a guide limiting the motion of the cutter and conforming in outline to the cross section of the tunnel, a belt conveyer, power driven rollers for driving said conveyer, and a telescopic shaft driven by said 40 rollers for rotating said cutter.
9. An excavator for tunneling, comprising in combination a sliding frame, guides on which said frame is advanced or retracted, a belt conveyer, a telescopic shaft driven from 45 the said conveyer, a cutter carried by the said frame and rotated by the said telescopic shaft and a guide for the said cutter conforming in outline to the cross section of the tunnel mounted on the said frame.
- 50 10. An excavator for tunneling, comprising in combination a frame sliding on rails, a belt conveyer, a telescopic shaft driven by rollers from the said conveyer and provided with universal joints at each end, a member
- carrying a cutting tool, rotated by the said 55 telescopic shaft and supported on the said frame so as to be freely movable about a horizontal and also about a vertical axis, and a guide limiting the movements of the said cutting tool and conforming in outline to the cross section of the tunnel. 60
11. An excavator for tunneling, comprising in combination a cutter, means for operating the cutter in any plane, a guide limiting the motion of the cutter and conforming 65 in outline to the cross section of the tunnel, a tubular worm conveyer, a belt conveyer and a hopper provided with a vent to which receptacles for receiving excavated material can be applied. 70
12. An excavator for tunneling, comprising in combination a sliding frame, guides on which the said frame can be advanced and retracted, a belt conveyer, a cutter carried by the said sliding frame and means 75 for rotating the cutter from the belt conveyer.
13. An excavator for tunneling, comprising in combination a sliding frame, guides on which the said frame can be advanced or 80 retracted, a belt conveyer, a cutter carried by the said sliding frame and means for rotating the cutter from the belt conveyer, sections of flooring supporting the sliding frame and sections of hinged tunnel linings 85 on which the sections of flooring rest.
14. An excavator for tunneling, comprising in combination a frame, guides on which the said frame slides, a belt conveyer, a telescopic shaft driven by rollers from the said 90 conveyer and provided with universal joints at each end, a member carrying a cutting tool, rotated by the said telescopic shaft and supported on the said frame so as to be freely movable about a horizontal and also 95 about a vertical axis, and a guide limiting the movements of the said cutting tool and conforming in outline to the cross section of the tunnel, said cutting tool being movable into any position within the limits prescribed by said guide. 100

In testimony whereof I have signed my name to this specification in the presence of two subscribing witnesses.

AUSTIN HOPKINSON.
